CLAIM

The ornamental design for an automobile tire, as shown and described.

DESCRIPTION

FIG. 1 is a front elevation view of an automobile tire showing our new design it being understood that the tread pattern is repeated uniformly throughout the circumference of the tire;

FIG. 2 is a side elevation view thereof, the opposite side being a mirror image of that shown;

FIG. 3 is an enlarged fragmentary plan view thereof; and

FIG. 4 is a cross sectional view taken along line 4—4 in FIG. 3.

FIG. 4
